UNITED STATES PATENT OFFICE.

ELISHA SEYMOUR AND CHARLES E. SHATTUCK, OF CLINTON, IOWA.

DESIGN FOR CHAIR-FRAMES.

Specification forming part of Design No. 6,458, dated February 25, 1873.

To all whom it may concern:

Be it known that we, ELISHA SEYMOUR and CHARLES E. SHATTUCK, of Clinton, Clinton county, State of Iowa, have invented a Design for the front legs or posts of a chair; also, the front stretcher to a chair; also, the arms and top of the back of a chair; of which the following is a specification:

The nature of our design is fully illustrated to which reference is made by the accompanying photograph.

A A represent the front legs or posts; B, the stretcher; C C, the arms; and D, the top of the back. The posts or legs A A are made square, varying in size according to the size of the chair, generally the same size the entire length, but may be made smaller at the bottom with a gradual taper. They may be made with turnings at different places on the leg or post, so as to form more than one square place on the leg. The corners of the post or legs

may be hollowed out, as represented in the photograph. The stretcher B is also made square and of such size as most suitable for the chair, and it may be turned at different places so as to form more than one square, and also the square may be of such size as the size of the chair requires. The arms C C are shown in the photograph; also, the top of the back D, the top being made an ogee with a cap projecting over the ogee, as indicated in the photograph.

What we claim as our design is—

The square posts and square stretcher for the front post and stretcher of a chair, and the peculiar shape of the arms and top of the back of a chair, as described and shown.

ELISHA SEYMOUR.
CHARLES E. SHATTUCK.
